FIG. 2

UNITED STATES PATENT OFFICE

2,580,356

CORK PISTOL

Gayle Martin, Milwaukee, Wis.

Application February 3, 1949, Serial No. 74,445

5 Claims. (Cl. 124—14)

1

This invention relates to a cork pistol.

It is the primary object of the invention to provide a novel and improved cork popgun construction in which the cylinder handle and trigger guard are of two-piece plastic construction having integral dowel and socket means for connecting them together and providing without bolts screws or the like for the mounting of the trigger, trigger spring, plunger release and plunger.

Since the improvements are concerned with specific details of construction, they will best be understood by reference to the following disclosure of the invention.

In the drawings:

Fig. 1 is a view partially in side elevation but largely in vertical section through a device embodying the invention.

Fig. 2 is a view taken in transverse section on the line 2—2 of Fig. 1.

Fig. 3 is a fragmentary detail view in perspective showing the trigger, trigger spring, plunger release and plunger.

Fig. 4 is a view in front end elevation of the component molded parts which are assembled in the completion of the gun.

Fig. 5 is a plan view of the respective molded parts prior to assembly.

The gun, which preferably takes the form of a pistol, comprises a gun barrel 6 having a pistol grip handle at 7 and a trigger guard at 8. The gun barrel comprises a cylinder within which there is operable a piston 9 comprising suitable conventional packing held by head washers 10 at the end of the plunger 11. Seated against the head washers and against the inner end of the cylinder is a compression spring 12 which develops sufficient air pressure ahead of the piston when the plunger is released so that ultimately the cork 13 is ejected with considerable force.

At the rear of the gun barrel ways or bearings are provided at 14 and 15 for the guidance of the plunger. The rear end of the plunger has a handle knob at 16. Intermediate its ends the plunger is relieved at 17 to provide a shoulder at 18 which may be engaged by the plunger release plate 19 to hold the plunger in its retracted position pending manipulation of the trigger 20. The detent plate 19 is normally held in its lowered position as shown in Fig. 1 by means of the trigger spring 21, such spring comprising, preferably, initially flat bit of clockspring connected at its forward end portion 22 with the upper margin of the trigger and having an intermediate portion 23 bent upwardly to engage the

2

gun barrel or other convenient stop, the extreme end portion 24 of the spring being engaged with the trigger guard or other stop opposed to the gun barrel. A spring thus made requires no anchorage but floats within the confined space in which it is located, biasing the trigger to oscillate clockwise as viewed in Fig. 1 about the trigger pintle 25. The finger 26 at the rear end of the trigger is engaged through an aperture

19 in plate 19 to draw the plate downwardly in response to the bias of the trigger spring. When the operator's finger is inserted through the trigger guard and used to manipulate the trigger in a counterclockwise direction as viewed in Figs. 1 and 3, the detent plate 19 is raised, thereby freeing the shoulder 18 of the plunger 11 and allowing the spring 12 to force the piston forwardly, thereby compressing air and ejecting the cork.

20 The barrel and the trigger spring chamber and the handle 7 are desirably molded in two parts which are united along a median plane, as clearly shown in Figs. 4 and 5. These parts not only are complementary to each other in the sense that one is "right" and the other "left." In addition, each part comprises features which the other does not have. For example, the molded part 28 which is shown at the left in Fig. 4 and at the left in Fig. 5, carries the forward sight 29 on the gun barrel, and also provides the trigger guard 8 to which reference has already been made. To assure that the gun barrel will be airtight throughout its length, the part 28 has grooves 31 and 32 along the opposite margins of the semi-tubular barrel portion 65, while the part 30 has complementary ribs at 33, 34, along the margins of its semi-tubular barrel portion 68. The part 28 is provided with dowels at 25, 35, 36, 37, 38 and 39 for which the part 30 has complementary sockets at 40, 41, 42, 43, 44 and 45 respectively.

46 The respective parts together provide the guideways at 14 and 15 for the plunger 11 and the transverse ways for the detent plate 19. Together the parts also provide cavities which, in the assembled gun, constitute the trigger spring chamber 46 beneath the barrel.

47 To assure proper alignment of the parts and to preclude separation of the component halves of the gun barrel, I have found it important to locate the dowels and their complementary sockets substantially at the precise points indicated, the dowel 35 being beneath the forward portions of the barrel and the dowel 25, which 55 also serves in the instant device as the trigger

pintle, being located beneath the rear portion of the barrel. The dowel 39 is at the extreme rear end of the gun beneath the barrel while the dowels 37 and 38 are centrally disposed in the lower end of the handle grip 7.

The component molded parts are assembled to each other with cement after the plunger, the piston with the piston spring, the detent plate 19, the trigger 20 and the trigger spring 21 have been deposited in one of the parts to be confined by the other. The cement used is preferably a solvent for the plastic so that, instead of being merely cemented together, the parts become, in effect, fused integrally as indicated by the lack of any parting line in Fig. 2. The dowels and ribs are desirably located exactly as shown and, being coated with the solvent, interlock each part with the other in addition to guiding the parts into perfect registry during assembly.

The resulting gun is strong and light and the barrel and other parts are free of warping which has been found to occur where any attempt is made to bolt or screw plastic parts to each other. The manner in which the trigger spring is formed and confined, and the manner in which the trigger is pivoted upon one of the dowels, makes it unnecessary to use metal bolts or screws even for the mounting of these parts.

I claim:

1. A popgun having a compartmented interior comprising the combination with a cylinder barrel, of a handle in integral connection therewith and including laterally spaced walls providing adjacent said barrel a trigger and trigger spring chamber said barrel and chamber having a common dividing wall, pintle means spanning said chamber below the barrel, a trigger pivoted on said pintle means, and a spring in impositive connection with said chamber having a portion engaging a chamber wall remote from the dividing wall, another portion engaging the trigger for the biasing thereof and a bend intermediate its ends engaged with the dividing wall, a plunger reciprocable in the barrel, a spring urging said plunger outwardly in the barrel, a detent for confining said plunger in a position rearwardly of the barrel, and a connection from the trigger to said detent for biasing the detent toward plunger confining position subject to the thrust of said trigger spring.

2. A popgun comprising integrally a barrel cylinder and handle, the handle being hollow and providing a trigger and trigger spring chamber beneath the barrel, a detent slide disposed transversely of the barrel and extending into said chamber, said barrel being provided with ways in which the slide is reciprocable, a trigger pro-

vided with a fulcrum extending transversely of the chamber, said trigger projecting from the handle at one side of the fulcrum and being connected with said detent slide at the other side of the fulcrum, a spring connected with the trigger and confined under pressure within said chamber, said spring being of angular form with an intermediate bend giving it three contact points disposed respectively at and intermediate its ends, said spring being engaged at one of said points with the trigger and the other two points with opposed wall portions of the chamber, a plunger reciprocable in the barrel and having a shoulder engageable with said detent slide, the slide having an opening through which said plunger passes, a spring confined within the handle about the plunger, a piston head against which said spring is seated, said head including means in substantially airtight engagement within the barrel, and a handle at the end of said plunger outside of said barrel for retracting said plunger against the compression of the spring.

3. The device of claim 2 in which the cylinder barrel and handle comprise two prefabricated side portions integrally united upon a common median plane, one of said portions being provided with dowel pins integral therewith and the other having sockets within which said pins are engaged.

4. The device of claim 2 in which three of said dowel pins are beneath the barrel at points spaced longitudinally thereof and two more are located in the handle below said chamber, one of said three dowel pins providing the trigger fulcrum aforesaid.

5. The device of claim 4 in which only one of said prefabricated portions integrally provides a trigger guard.
